RAYMOND J. NORTON, OF WASHINGTON, DISTRICT OF COLUMBIA, ASSIGNOR TO BENDIX AVIATION CORPORATION, OF SOUTH BEND, INDIANA, A CORPORATION OF DELAWARE

HYDROBRAKE

Application filed July 2, 1930. Serial No. 465,408.

This invention relates to a retarding mechanism and more particularly to a hydro brake for seaplanes and flying boats.

It is sometimes desirable to retard the speed 5 of a seaplane or flying boat, when taxiing upon the water and also to increase its maneuverability on the water. Another factor which is of importance in this type of structure is the take-off ability of the ship 10 from the water.

A major object of the present invention is to provide a mechanism which incorporates the advantageous features of increasing the hydroplaning effect, and thereby giving a 15 better take-off, and also controlling or regulating both the speed and direction of the craft when maneuvering upon the surface of the water.

Another object is to provide a hydro brake. 20 A further object is to provide combined hydroplaning and water braking surfaces.

A further object is to provide an optionally operable mechanism for increasing the lift effect upon the float structure of a seaplane or 25 flying boat.

With these and other objects in view the invention comprehends the provision of an element or elements so designed and arranged with respect to the float mechanism of a seaplane as to serve either as a hydroplaning surface or as a water brake.

In order to clarify the description of the invention a typical physical embodiment of it is shown, diagrammatically, in the accompanying drawing in which:

Figure 1 is a side elevation of a seaplane in which the improvement is embodied;

Figure 2 is an enlarged detail of the hydro brake;

Figure 3 is an enlarged detail of a modified form of the hydro brake; and

Figure 4 is a cross section taken on line 4—4 of Figure 3.

It is advantageous, for a number of reasons, to provide a mechanism, associated with the float or hull of a seaplane or flying boat, which may be made to act with the water to retard the speed of the ship on the water. Due to the fact that the slip stream effects of a single screw ship causes a sluggish ma-

neuver in one direction it is desirable to provide means for counteracting this effect, that is to say, to increase the dirigibility of the plane when maneuvering upon a water surface. It is also advantageous, as is well known, to provide a means for increasing the lifting or hydroplaning effect upon the float or pontoon of flying ships, and also to brake or minimize the adherence between the float and the water at the moment of take-off. All of these advantages are subserved by the apparatus hereinafter to be described.

In accordance with the present invention a mechanism is provided which when moved in one position functions to increase the lift 65 upon the hull and when moved to another position to act as a retarding means for the ship.

As shown in Figure 1 this improvement may be associated with a seaplane which may comprise such conventional elements as the 70 fuselage 1, sustentation surface or surfaces 2, propelling mechanisms 3 and empennage 4. The water sustaining surface 5 may comprise a single central hull or a plurality of pontoons of the usual type, having a cruising bow 6 and special hydroplane bottoms. The water sustaining surfaces may be secured indirectly or immediately to the fuselage through any suitable type of supporting 75 structure indicated on the drawing by the float struts 7, 8, and 9. The pontoon or float structure may be constructed of any suitable material such as single or double bottom hulls of wood or light weight alloys such as duralumin.

In accordance with the present invention the hull or body structure is reinforced as by the ribs 10 and 11 and stanchion element or elements 12. The pontoon is provided with a sealed well 13, formed between the stanchions 12 in which operates the novel hydro brake 14. This element may comprise a member having relatively wide surfaces 15 and 16, which have sliding engagement with the sides 95 of the well. The friction between the sliding surfaces may be diminished by any suitable anti-friction means. This hydro brake is provided with a bottom portion 17, which is designed in a manner well known to those skilled in the art to serve as a lifting or 100

hydroplaning surface when brought into operative position with respect to the water surface as indicated by the position 17a.

The hydro brake is provided with an actuating mechanism which may be operated so as to cause the hydro brake to function either as a hydroplaning surface or as a water retarding means or brake. It will be appreciated that a relatively wide variety of mechanisms may be utilized for this purpose.

The typical embodiment in the drawing comprises an actuator 18, which reciprocates within a casing 19. At one end this actuator is secured to a piston rod 20. A piston 21 is formed on the end of the piston rod, which is reciprocated within a cylinder 22 under the action of air or other suitable fluid admitted through the conduit 23 from a suitable source of supply. In lieu of the hydraulic or pneumatic actuator mechanical means may obviously be employed.

The actuating element 18, as shown, is provided with a plurality of cam surfaces 24 and 25 and an intermediate horizontal surface 26. Positioned respectively on the hydro brake element 14, and an adjacent section of the pontoon, are the anti-friction rollers 27. Connected with the brake element and a fixed section of the pontoon is a retracting spring 28, which, as will be readily understood, serves to return the brake element into its inoperative position.

The operation of the device will be appreciated from the described relationships of the elements. When it is desired to increase the hydroplaning effect the lever, or other operating element, may be displaced to cause longitudinal movement of the actuator 18. Rearward movement of this member causes the cam surfaces 24 to engage the rollers and to depress the member 14 against the action of the retracting springs 28. This downward movement continues until the horizontal portion 26 engages the rollers. In this position of the operating mechanisms the lower hydroplaning surfaces, 17, of the brake element takes the approximate position shown by the dotted line, 17a, in Figure 2. In this position the bottom portion of the brake serves as a hydroplane surface to increase the lift upon the float or pontoon. It will be appreciated that if such operation is effected at the time it is desired to take off from the water the increased lifting effect will facilitate this upward movement. This breaking of the adhesion between the water and the float at the moment of take-off is accentuated by positioning the element adjacent the step section, 29, of the float.

When it is desired to utilize the element as a brake the operating pedal, or similar actuating member, is additionally displaced to cause the element 14 to be moved downwardly under the action of the cam surface 25. As the member 14 moves downwardly from

the dotted line position, shown at 17a, to the fully applied position, shown at 17b, a positive retarding force will be set up due, as will be appreciated, to the resistance to movement offered by the front section 15.

It will, therefore, be appreciated that this mechanism may be used optionally as a hydroplaning surface or as a hydro brake.

Preferably the brake is positioned in the rear of the center of gravity of the ship so as to minimize the tendency of the plane to nose downwardly upon application of the brakes. If desired, the elements 14 on each of the pontoons may be separately operated so as to obtain a steering or directive effect.

It will be appreciated that the lifting effect of the hydroplane surface 17 may be adjusted or varied to suit any set of conditions. Such a mechanism is shown in Figures 3 and 4. In this circumstance the hydro brake may comprise the casing member having top section 30 and side section 31. The bottom or hydroplaning section 32 is pivoted at the front end by means of the pivot 33 to the front casing wall. The rearward portion of the hydroplaning surfaces may be formed as a segmental section 34, which abuts a similarly formed surface 35 on the rearward wall of the member. With this hydroplaning surface may be associated an adjusting mechanism which may be actuated to set the surface 32 at any desired angularity. As shown in the drawing this may take the form of a plurality of links, 36, pivotally connected respectively to the hydroplaning surface 32 and to the vertically adjustable links 37. These links may be internally threaded to receive the adjusting bolts 38. These bolts have a smooth section 39 freely rotatable in the top wall 30 of the hydro brake, and a knurled or angularly configured top 40. It will be appreciated that by rotation of the bolts, 38, the hydroplaning surface 32 may be elevated or depressed to give any desired angularity.

It will now be appreciated that there has been provided a relatively simple mechanism which may subserve a plurality of useful function, for, as noted hereinbefore the device is adjusted at the volition of the operator to act as a means for increasing the hydroplaning effect or as a water brake to retard the speed of the ship in maneuvering upon the water.

While one embodiment of the invention has been described it is to be understood that this is given merely as an example of any mechanism which will subserve the described functions or achieve the desired results.

I claim:

1. A sea plane having pontoons, a member, having a hydroplane surface and a braking surface mounted on each pontoon and operable to serve as a hydroplane surface or as a water brake.

2. A sea plane having pontoons, independently operable members, having a hydroplane surface and a braking surface mounted on each pontoon, operating means for each member adapted to move it either into a position to serve as a hydroplane surface or as a hydro brake. 70
3. A flying ship having a fuselage and a water sustaining surface, a member, having a hydroplane surface and a braking surface mounted at a point laterally spaced from the longitudinal axis of the ship adapted to serve as a hydroplane surface or a hydro brake. 75
4. A flying ship having a fuselage and a float mechanism, a member, having a hydroplane surface and a braking surface mounted at a point laterally spaced from the longitudinal axis and rearwardly spaced from the center of gravity of the ship to serve as a hydroplane surface or a water brake. 80
5. A sea plane having twin pontoons, a member, having a hydroplane surface and a braking surface mounted on each pontoon and spaced outboard of the longitudinal axis of the plane adapted to serve as a hydroplane surface or a water braking surface. 85
6. A sea plane having twin pontoons, a member, having a hydroplane surface and a braking surface mounted on each pontoon and spaced outboard of the longitudinal axis of the plane and rearwardly of its center of gravity adapted to serve as a hydroplane or a hydro brake. 90
7. A sea plane having water sustaining surfaces, independently operable members, having a hydroplane surface and a braking surface mounted outboard of the longitudinal axis of the plane and rearwardly of its center of gravity, each member being adapted in one operative position to serve as a hydroplane surface and in another as a hydro brake. 95
8. A sea plane having a pontoon, a member having a combined hydroplane and hydro brake surface and means for moving said member to an inoperative position within the contour of the pontoon to preserve the stream line effect when flying in air. 100
9. A sea plane having a pontoon, a member, having a hydroplane surface and a braking surface, and means to move said member to an inoperative position within the contour of the pontoon to preserve the stream line effect when flying in air and to move said member outwardly of the contour of the pontoon when cruising on the water to serve as a hydroplane surface, a hydro brake or a sea rudder. 105
10. A sea plane having a pontoon and member, having a hydroplane surface and a braking surface mounted directly thereon adapted to function as a hydroplane surface, a hydro brake or a sea rudder. 110
11. A flying ship for a water sustaining surface, a member retractably mounted on 115
